CURTIS B. ILGENFRITZ, OF PITTSBURGH, PENNSYLVANIA

DESIGN FOR A LIQUID DISPENSER OR SIMILAR ARTICLE

Application filed January 21, 1931. Serial No. 38,404. Term of patent 14 years.

To all whom it may concern:

Be it known that I, CURTIS B. ILGENFRITZ, a citizen of the United States, residing at Pittsburgh, in the county of Allegheny and State of Pennsylvania, have invented a new, original, and ornamental Design for Liquid Dispenser or Similar Article, of which the following is a specification, reference being had to the accompanying drawing, forming part thereof.

Figure 1 is a front elevation of a dispenser embodying my design, a portion of the lid being broken away to show the contour thereof;

Figure 3 is a top plan view thereof, the upper portion of the lid being broken away to show a section through the front of the dispenser body.

I claim:

The ornamental design for a liquid dispenser or similar article, substantially as shown.

CURTIS B. ILGENFRITZ.
